UNITED STATES PATENT OFFICE.

JAMES K. RICHIE, OF BUTLER, PENNSYLVANIA.

TALLY BOOK.

Application filed October 21, 1925. Serial No. 63,927.

This invention aims to provide a novel means whereby a person can keep track of money spent, or of any other sum, it being possible to ascertain the total expenditure at anytime without difficulty.

Figure 1 shows in perspective, a device constructed in accordance with the invention; Figure 2 is a cross section; Figure 3 is a longitudinal section; Figure 4 is a plan wherein the binder has been opened out flat; Figure 5 is a similar view, with the wings of the cover open; Figure 6 is a similar view wherein some of the tabs have been torn off.

15 The numeral 1 marks a flexible binder including a body 2 and foldable overlapped flaps 3, one flap having a pocket 30, and the flap being connected, when closed, by a detachable fastener 4.

20 The numeral 5 designates the back of a book 6, the back being cemented or secured otherwise to the body 2 of the binder 1, the book comprising leaves 7 superposed on the back 5 and equipped in their longitudinal edges with notches 8 defining tabs 9. A stiff index plate 10 is superposed on the outermost leaf. The index plate is considerably narrower than the leaves 7. On the index plate 10 is placed a cover 11 which is about 25 as wide as the leaves 7. Staples 12, or any other connecting means, unite the central portion of the cover 11 with the index plate 10, the leaves 7 and the back 5. A guard strip 14 covers the outer ends of the staples 12 and is cemented or secured otherwise to the cover 11. The guard strip 14 is considerably narrower than the cover 11. The cover 11 is foldable along the longitudinal edges 15 of the guard strip 14 to form wings 40 16. In Figures 5 and 6, the wings 16 of the cover 11 are shown turned out at right angles to the index plate 10.

45 There are longitudinal lines of numerals 17 on the index plate 10 adjacent to the longitudinal edges of the plate. The numbers 17 increase progressively in value, longitudinally of the index plate. The tabs 9 in each stack have numerals 18 which increase progressively in value from the outermost tab of each stack to the innermost tab of each stack, by steps which correspond to the numerals on the index plate; for instance, the 25¢ tabs are numbered 25, 50, 75, etc. This can be seen at 19 in Figure 6, for instance, where three tabs in the 25¢ stack have been torn off, leaving the 75¢ tab

exposed; it being observed, as shown at 20 in Fig. 5, that the outermost tabs are marked zero, so that when, for instance, 25¢ is spent, and the outermost tab is torn off, the amount 60 of 25¢ will appear on the tab next beneath, thus indicating that 25¢ have been spent.

The operator opens the binder 1 into the position of Figure 4, swings the wings 16 of the cover 11 open, as in Figures 5 and 6, 65 notes the numerals 17 on the index plate 10, and tears off, across the edges of the index plate 10, tabs 9 the numerals 18 of which foot up to the amount that has been expended.

70 Note the right hand side of the book 6 in Figure 6. The tabs remaining read as follows:—

.05	75
.10	
.20	
.30	
.50	
3.50	80
2.00	
10.00	
8.00	
\$24.65	

thus indicating that the sum of \$24.65 has 85 been spent. Owing to the double form of the book 6, two separate accounts can be carried. Although money values have been shown, a tally involving other numerical values can of course be reckoned. The 90 notches 8 are wide enough to give ready access to the tabs 9, so that the tabs can be picked up in the fingers and torn off across the index plate 10, but they are not so wide as to produce a waste of paper.

95 What is claimed is:—

1. In a device of the class described, a back, leaves mounted on the back, an index plate mounted on the leaves and narrower than the leaves, a cover mounted on the index plate and approximating the leaves in width, a fastener connecting the cover, the index plate, the leaves and the back, a guard strip mounted on the cover and narrower than the cover, the guard strip housing the fastener, the index plate being provided with longitudinal lines of numerals, said numerals increasing progressively in value longitudinally of the plate, the cover being foldable along the longitudinal edges of the 110 guard strip to expose said numerals, the leaves being provided in their opposite edges

with notches which define stacks of tabs, the tabs being severable by tearing them across the edges of the index plate, and each stack of tabs being provided with numerals which 5 increase progressively from the outermost tab of each stack to the innermost tab of that stack, by steps of which one of the numerals on the index plate is a unit of reference.

2. In a device of the class described, a 10 back, leaves mounted on the back, an index plate mounted on the leaves and narrower than the leaves, a cover mounted on the index plate and approximating the leaves in width, means for fastening together the cov- 15 er, the index plate, the leaves and the back, the index plate being supplied with longitudinal lines of numerals, said numerals increasing progressively in value longitudinally of the plate, the cover being foldable 20 along spaced longitudinal lines to expose said numerals, the leaves being provided in their opposite edges with notches which form stacks of tabs, the tabs being severable by tearing them across the edges of the index plate, each stack of tabs being provided with numerals which 25 increase progressively from the outermost tab of each stack to the innermost tab of that stack, by steps of which one of the numerals on the index 30 plate is a unit of measurement.

3. In a device of the class described, a

plurality of superposed leaves, an index plate mounted on the leaves and narrower than the leaves, a cover mounted on the index plate and approximating the leaves in 35 width, a fastener connecting the cover, the index plate and the leaves, a guard strip mounted on the cover and narrower than the cover, the guard strip housing the fastener, the index plate being provided with longitudinal lines of numerals, said numerals increasing progressively in value longitudinally of the plate, the cover being foldable 40 along the longitudinal edges of the guard strip to expose said numerals, the leaves 45 being provided in their opposite edges with notches which form stacks of tabs, the tabs being severable by tearing them across the edges of the index plate, each stack of tabs being provided with numerals which 50 increase progressively from the outermost tab of each stack to the innermost tab of that stack, by steps of which one of the numerals on the index plate is a unit of measurement, a binder comprising a body and opposite 55 disposed flaps, the leaves being mounted on the body, and the flaps being folded over upon each other and upon the guard strip.

In testimony that I claim the foregoing as my own, I have hereto affixed my signature.

JAMES K. RICHIE.
